[57] **CLAIM**

The ornamental design for a baby pacifier, as shown and described.

DESCRIPTION

FIG. 1 is a front elevation view of a baby pacifier showing my design;

FIG. 2 is a rear elevation view thereof;

FIG. 3 is a right side elevation view thereof;

FIG. 4 is a left side elevation view thereof;

FIG. 5 is a top plan view thereof;

FIG. 6 is a bottom plan view thereof; and,

FIG. 7 is a front perspective view thereof, in use condition, the broken line showing of the person's head being for illustrative purposes only and forming no part of the claimed design.
